CHAIN LINK FENCE-MAKING MACHINE OR THE LIKE

Harrison B. Mayfield, 12737 Mitchell Ave.,
Los Angeles, Calif. 90066

Filed Jan. 31, 1968, Ser. No. 10,373

Term of patent 14 years

Int. Cl. D15—05

U.S. Cl. D55—1

FIG. 1 is a perspective view of a chain link fence-making machine or the like embodying my new design;

FIG. 2 is a rear elevational view thereof;

FIG. 3 is a side elevational view illustrating the side of the machine which is not visible in FIG. 1; and

FIG. 4 is a top plan view thereof.

I claim:

The ornamental design for a chain link fence-making machine or the like, substantially as shown.
